MULTICOLOR JOB OR PROOF PRESS

J Russell Parrish, Des Moines, Iowa, assignor to
 Meredith Publishing Company, Des Moines,
 Iowa, a corporation of Iowa

Application February 17, 1951, Serial No. 211,472

6 Claims. (Cl. 101—174)

1

This invention relates to a multi-color printing press for use either in the proofing of curved rotary press plates or for job printing, although the invention is not necessarily limited to those uses. This particular application is a continuation-in-part of application Serial No. 51,400, filed September 27, 1948, now abandoned.

Large rotary presses for printing magazine color sheets may, for example, print hundreds of thousands of the same color sheets on one run. These large presses take considerable time to set up for printing, and this so-called make-ready time may take one hundred or more man-hours before the press can be started. This is expensive not only because of the time in labor, but also because the press is not producing during the make-ready time. Furthermore, if there is anything wrong with one or more of the printing plates, it does not show up until a run is started, and thereafter if even a single plate must be removed for correction, the press must be shut down all during the time the correction is made. For the above reasons, proof presses have been devised to test the plates prior to their being disposed on the main press.

The available proof presses also have certain disadvantages. Under present methods of curved plate proofing, a single color proof is pulled by hand off each plate. Usually these are in black ink, so that neither the color may be proofed, nor may the final result in two, three or four colors be seen until the main press is run.

It is therefore, an object of the invention to provide an improved multi-color press which may be used as a proof press.

It is also an object of the invention to provide a multi-color proof press in which plate register may be determined prior to sending the plates to the pressroom and prior to attaching them to the main press. Therefore, if certain plates must be cut and leveled, this may be done in advance, thus reducing the make-ready time on the main presses. If necessary to make new plates, they may be ordered when proofed instead of waiting until the run is started.

It is further an object of the invention to provide a multi-color proof press on which the interchangeability of spare plates with regular sets may be checked in advance of press runs, thus saving press time during a run.

It is an additional object of the invention to provide a multi-color proof press in which the results to be obtained from the use of certain inks, the comparative tone intensities for each color and the selection of the proper underlay

may all be checked in advance of placing the plates on the main press.

It is a further object of the invention to provide a multi-color proof press on which perfect register checking may be obtained on a plate proof, since the sheet does not leave the gripper bars of the impression cylinder until all the colors are printed. Furthermore, the wet inking process used on multi-color high speed presses may also be used on a proof, thus obtaining close to true press conditions on a proof press.

It is further a very important object of this invention to provide a multi-color proof press in which the colors are printed in proper sequence and where the proof is printed as the finished product will be, and not reversed.

With respect to job presses under present methods, small runs of multi-color work are very expensive and time consuming. On present job presses, each color is placed on a sheet separately and allowed to dry before the next color is put in. Two-color presses are quite common but require two runs for four-color work, with a wasted time interval between colors. Drying usually takes from one to two days. Furthermore, paper shrinks and expands due to varying temperature and humidity conditions, so that perfect register is very seldom obtained. In addition, it is impossible to see the final result until the last color is placed on the sheet. Large high speed multi-color presses are too expensive for the average job printer.

It is an object of the invention, therefore, to provide a multi-color press which is adapted to job printing and which is relatively inexpensive.

It is another object of the invention to provide a job printing multi-color press on which the finished result may be seen at the beginning of the job, on which make-ready work may be done at one time and on which better quality of multi-color printing from a register standpoint is obtained.

It is also an object of the invention to provide a multi-color job press on which the waiting time for drying between colors is eliminated and the total running time is decreased.

It is a further object of this invention to provide a multi-color job press having a plurality of printing plates, each of a different color, upon one or more plate cylinders, which job press prints the colors in the same specified sequence and upon the same specified portions of all the sheets being printed.

It is a very important object of the invention to provide a multi-color press in which the cor-

relation between the diameters of the one or more plate carrying cylinders with the diameter of the impression cylinder is such that the ratio between the impression cylinder diameter and the diameter of the plate cylinder or cylinders is an aliquant number. In other words, the ratio must be such that when the smaller number is divided into the larger number, a fraction is always left over. When such ratio obtains, the successive various color plates on the plate cylinder or cylinders successively contact one and the same area on the impression cylinder, whereby a sheet of paper placed on the particular area will receive successive imprints of different colors always in the same predetermined sequence.

It will be recognized that the ratio between the circumference of the impression cylinder and the circumference of the plate cylinder is the same aliquant number as the ratio of the diameter of the impression cylinder and the diameter of the plate cylinder, since the circumference of a cylinder is merely π times the diameter. Since segments of the impression cylinder and plate cylinder must repeatedly coincide in predetermined sequence during a printing run, the circumference may be defined in terms of these segments and a unit of circumferential length will be defined in terms of an impression surface on which the sheet to be printed is mounted, or in terms of a plate surface which carries the ink. This unit of circumferential length is an aliquot part of both the circumference of the impression cylinder and the circumference of the plate cylinder. In this specification, the relationship of impression surfaces to plate surfaces will be taken up and described, as such relationship is simpler than a discussion of the relationship of the diameters of the impression and plate cylinders.

With these and other objects in view, my invention consists in the construction, arrangement and combination of the various parts of my device whereby the objects contemplated are attained, as hereinafter more fully set forth, pointed out in my claims and illustrated in the accompanying drawings wherein:

Figure 1 is a perspective view of a multi-color press illustrating one embodiment of the invention;

Figure 2 is a diagrammatic view of the press shown in Figure 1, also showing the relative position of the press to the blank stock supply and to the printed stock;

Figure 3 is a diagrammatic view of a press constructed in accordance with a second embodiment of the invention;

Figure 4 is a schematic view of the grippers and the actuating mechanism therefor, and is taken looking upward from beneath the impression cylinder 41 as shown in Figure 3;

Figure 5 is a diagrammatic view of a gripper in closed position;

Figure 6 is a diagrammatic view of a gripper in an open position;

Figure 7 is a diagrammatic view of the tumbler used to open and close the grippers showing the position of the tumbler just before it closes the grippers;

Figure 8 shows the tumbler just after the grippers are closed;

Figure 9 shows the tumbler just before the grippers are opened;

Figure 10 shows the tumbler just after the grippers are opened;

Figure 11 is a side elevation of the multi-color job and proof press shown in Figure 3, illustrat-

ing an operating mechanism and typical cam arrangement for reciprocating the tumbler actuating pins;

Figure 12 is a view of a portion of the operating mechanism for the tumbler actuating pins and is taken on line 12-12 of Figure 11;

Figure 13 is a detailed drawing of a cam shown in Figure 11;

Figure 14 is a side elevation of the multi-color job and proof press shown in Figure 2, illustrating an operating mechanism and typical cam arrangement for reciprocating the tumbler actuating pins;

Figure 15 is another view of the operating mechanism and gear arrangement for the tumbler actuating pins, and is taken on line 15-15 of Figure 14.

Referring to the drawings, the following general observations are true with respect to the embodiments of the invention shown. As is true with any other job or proof press utilizing rotary plate cylinders, the diameter of the plate cylinder is determined by the dimensions of the press over which the plates are made to fit. Therefore, in speaking of ratios between the impression cylinder diameter and the plate cylinder diameter, the plate cylinder diameter will always be the determining factor. In some designs, the plate cylinder may be larger than the impression cylinder, and in others the impression cylinder may be larger than the plate cylinder.

Although the exact position of the plate cylinders around the impression cylinder is unimportant from the standpoint of many of the principles involved herein, the plate cylinders must preferably be positioned within a limited region so as to provide for opening of the grippers to discharge the printed sheet and later closing of the grippers for picking up a fresh sheet within a limited range of rotation of the impression cylinder. It is also important that the sheet being discharged from the impression cylinder be clear of the printing plates to the greatest extent possible, so that there is little chance of relative motion between the sheet and the last printing plate. The positioning of the plate cylinders with respect to the points where the sheets are picked up and discharged from the impression cylinder is shown in Figures 2 and 3. Since more than one color of ink is to be applied to each plate cylinder, the inking or form rollers may be engaged and disengaged by means of a cam (not shown) on the plate cylinder in a manner well known in the art.

As stated above, the designs shown herein differ from other printing presses by utilizing various fractional gearing ratios or diameter ratios, which ratios must be of some other value than 1:1. When the impression cylinder is run with the plate cylinder at any ratio other than 1:1, the smaller cylinder will contact different portions of the larger cylinder at each successive complete turn of the smaller one. It is also to be noted that in each design the paper sheet to be printed is carried by the surface of the impression cylinder. Therefore, for example, if the ratio is 3:2, a certain portion of the smaller cylinder will contact a different portion of the larger cylinder during each three revolutions of the smaller one. During the following three revolutions, this same cycle will be repeated in the same order. In such a case, by dividing the circumference of the smaller cylinder into two equal portions, and of the larger cylinder into three equal portions, the arc of each segment of both

cylinders will be the same length. It will also be noted that the number of impression surfaces will be odd or even, depending on the number of colors, although four color presses are the only ones shown. The number of impression surfaces will be odd when the number of colors is even, and will be even when the number of colors is odd.

There is a critical relationship among the following quantities: The number of printing plates (or colors to be printed), the number of plate cylinders, the number of sheets taken onto (or discharged from) the impression cylinder during a full cycle, the number of impression surfaces on the impression cylinder, and the number of revolutions of the impression cylinder necessary to have each printing plate register once with each impression surface (the number of revolutions of the impression cylinder per cycle). This relationship may be expressed in the form of an equation or formula which is generic to all the embodiments of the invention described herein or constructed in accordance with the principles herein set forth. That equation or formula is:

$$\frac{\text{Number of colors}}{\text{Number of plate cylinders}} \times \frac{\text{Number of sheets taken onto the impression cylinder during a cycle}}{\text{Number of revolutions of the impression cylinder per cycle}} =$$

$$\frac{\text{Number of impression surfaces}}{\text{Number of revolutions of the impression cylinder per cycle}}$$

Since each impression surface takes on one sheet during each cycle, it will be seen that:

$$\frac{\text{Number of sheets taken onto the impression cylinder during a cycle}}{\text{Number of impression surfaces}} = \frac{\text{Number of revolutions of the impression cylinder per cycle}}{\text{Number of impression surfaces}}$$

Thus, the generic equation can be more simply written as:

$$\frac{\text{Number of colors}}{\text{Number of plate cylinders}} = \frac{\text{Number of revolutions of the impression cylinder per cycle}}{\text{Number of impression surfaces}}$$

It should be pointed out that if more than one plate cylinder is used, the colors must be equally divided among the plate cylinders for the equation to obtain.

Referring specifically to Figures 1 and 2 for a description of the first embodiment of the invention, numeral 11 designates vertical frame members for a rotary press, and numeral 12 designates a combination bed plate and shelf upon which sheets are delivered to the impression cylinder. A shelf 13 is provided for receiving the printed sheets from the impression cylinder, which sheets have been given the numeral 31.

The impression cylinder is shown generally at 14 and the plate cylinders are shown at 15 and 16. The impression cylinder is rotated through a shaft 17 secured thereto and provided with suitable bearings in the frame members 11. The shaft 17 may be rotated by hand or by any suitable source of power.

A gear 18 is secured to one end of the impression cylinder 14 and is rotated by the shaft 17. The plate cylinder 15 is provided with a gear 19 and the plate cylinder 16 is provided with a gear 21, the gears 19 and 21 each being of the same size and both being smaller than the gear 18. The ratio of the pitch circle of gear 18 to 70 the pitch circle of gears 19 and 21 is 3:2. The gears 19 and 21 are rotated by gear 18. The plate cylinders 15 and 16 are provided with shafts 22 and 23, respectively, which are supported in suitable bearings in the frame members 11.

Movable sheet grippers 24 are provided in a recess 25 in the impression cylinder 14. In this embodiment, three sets of grippers 24 are provided, and these grippers pick up individual sheets 30 from the shelf 12 and release the printed sheets 30a at the proper time onto the shelf 13, that is, when the printing cycle is completed. The pickup and release of the sheets is effected by cam means which will be described herein-after.

The impression cylinder 14 is divided into three segments 26, 27 and 28, upon which the paper sheets are retained during the color printing operation. The plate cylinder 15 is provided with two printing plates 31 and 32 with undercut portions 33 therebetween. The plate cylinder 16 is likewise provided with two plates 33 and 34, leaving undercut portions 35 therebetween. The plate cylinder 15 is provided with two sets of inking rollers 36 and the plate cylinder 16 is provided with two sets of inking rollers 37. Each of the inking rollers places a different color on the plates at the proper time, in a manner well understood in the art. The spaces 38 between 20 the plates provide space to lower the inking rollers to inking position without inking the wrong plate and still fully ink the succeeding plate. The spaces 38 also provide for lifting of the inking rollers after the inked plate has 25 passed without inking part of the next plate.

Assuming that the four colors to be used are yellow, red, blue and black and are printed in that order upon each sheet, plate 31 is the plate for printing the yellow color; plate 32, red; plate 33, blue; and plate 34, black. It will be obvious that as the impression cylinder 14 is rotated, four colors may be proofed in one operation which comprises two revolutions of the impression cylinder. One of the sets of inking rollers 36 is 35 adapted to supply red ink to plate 32 and another set of inking rollers 36 is adapted to supply black ink to plate 31, in a manner well known in the art. Similarly, one of the sets of inking rollers 37 is adapted to supply yellow ink to plate 33 and the other set of inking rollers 37 is adapted to supply blue ink to the plate 34.

The ratio of the circumference of the impression cylinder to the circumference of the plate cylinders is 3:2. One-third of the circumference of the impression cylinder includes one of the impression surfaces plus a recess 25 within which grippers 24 are mounted. The arcuate length of surfaces 31, 32, 33 and 34 on plate cylinders 15 and 16 is substantially the same as the length of the impression surfaces 26, 27 and 28 on impression cylinder 14. The arcuate length of recessed portions 33 and 35 on plate cylinders 15 and 16 is substantially the same as the arcuate length of the recesses 25 in impression cylinder 14. Two recessed portions 33 and 35 are provided in each plate cylinder, one of said recessed portions 33 and 35 being associated with each plate portion 31, 32, 33 and 34. The arcuate length of the printing plates is substantially that of the arcuate length of the impression surfaces, and the arcuate length of recesses 33 and 35 is the same as the arcuate length of the recesses 25 in the impression cylinder, so that upon rotation of the cylinders the impression surfaces and the printing plates will always register with each other.

Figure 3 shows an embodiment which is particularly adaptable for a job press to provide four-color printing on a press having one plate cylinder and one impression cylinder. In this

case the impression cylinder shown at 41 is smaller than the plate cylinder shown at 52. The ratio of the circumference of the plate cylinder to the circumference of the impression cylinder in this case is 4:3. This design for four-color printing is limited to printing by plates having a curved length not exceeding one-quarter the circumference of the plate cylinder 52. Only one-third of the impression cylinder surface is used for each impression, and four revolutions of the impression cylinder will effect the transfer of all four colors.

As shown in Figure 3, the impression cylinder 41 is provided with three sets of grippers 42 disposed in recess 43 for picking up and releasing sheets of paper 30, in the same manner as described with respect to Figures 1 and 2. Three impression receiving surfaces 44, 45 and 46 are provided.

A stack of blank sheets 30 is shown at 47, which sheets are individually fed, in a manner well known in the art, over a surface 48 to a position where they will be picked up at the proper time by the grippers 42. The completed or printed sheets are also fed, in a manner well known in the art, over a surface 51 to a printed stack shown at 49. Sheet 30 is only released after four revolutions of the impression cylinder, so that all four of the plates shown at 53, 54, 55 and 56 on the plate cylinder will have contacted each sheet on the impression cylinder. The plates on the plate cylinder 52 are slightly spaced from each other to provide an undercut portion 57 therebetween. The undercut portion 57 is of the same circumferential length as the recess 43 in the impression cylinder and is positioned to register with this recessed portion 43 upon revolution of the cylinders, so that the printing plates will always register with the impression surfaces on the impression cylinder 41. Sets of inking or forming rollers shown at 58, 59, 60 and 61, one for each color, are provided and are operated in a manner stated hereinbefore, to apply the proper color ink at the proper time to each of the printing plates on plate cylinder 52.

For the purpose of this description, it will be assumed that the color of the ink carried by printing plate 53 is red; plate 54, yellow; plate 55, black; and plate 56, blue. It will also be assumed that the printing cylinder 52 rotates in a clockwise direction and the impression cylinder 41 rotates in a counterclockwise direction.

Referring now more particularly to the grippers which are associated with the impression cylinders to retain the sheets to be printed upon the impression surfaces of the impression cylinder, a plurality of the grippers 42 are mounted on a shaft 62, which shaft is journaled at points 63 and 64, illustrated in Figure 4. One end of the shaft 62 extends beyond the point where it is journaled, as at 65. This extended end 65 of shaft 62 has a tumbler 66 fixedly mounted thereon. The opening and closing of the grippers 42 is accomplished by arcuately moving the tumbler 66 about the axis of shaft 62, resulting in the arcuate movement of shaft 62 which is fixedly secured to the tumbler 66. Figures 5 and 6 respectively, show the closed and opened positions and indicate the range of arcuate movement of grippers 42 encompassed in the gripping and releasing of the sheet to be printed.

The tumbler 66, as illustrated in Figures 7, 8, 9 and 10 includes a central body portion from which extends a pair of spaced fingers 67 which form a pocket 68 therebetween, which pocket 68 is lo-

cated to one side of the point of securement of tumbler 66 to shaft 62. A second pair of fingers 69 also extends from the central body portion and bounds a pocket 70 located diametrically opposite the pocket 68.

When the impression cylinder rotates, the gripper shaft 62 and tumbler 66 rotates with the impression cylinder. A pair of tumbler actuating pins 71 and 72 are provided to actuate the tumbler 66 at the proper times to close and open the grippers 42, which pins are best shown in Figures 11 to 15. These actuating pins 71 and 72 are normally withdrawn from the path of the tumbler 66. At desired intervals these pins 71 and 72 are thrust into the path of tumbler 66 to be engaged by tumbler 66 and to cause the tumbler 66 to operate the grippers 42 to opened or closed position.

A portion of the frame of the proof press is designated at 73 and upon this frame the tumbler actuating pins and actuating mechanism therefor are mounted. Figures 11 and 12 illustrate an operating mechanism for the tumbler pins that may be used with the form of job and proof press shown in Figure 3. The grippers on proof presses usually are operated manually without the use of tumblers. Figures 14 and 15 show the type of mechanism that is used to actuate the tumbler pins for the form of job and proof press shown in Figures 1 and 2. For illustrating purposes, the actuating mechanism for the tumbler pins as shown in Figures 14 and 15 will be described.

Referring more specifically to Figures 14 and 15, the pins 71 and 72 are mounted in the frame structure 73 and are normally biased to a withdrawn position as is pin 71, which in Figure 15 is shown in full lines. The position when extended is shown by dotted lines and is indicated by 71a. The pins 71 and 72 are biased in the withdrawn position by means of springs 74 which are seated in pockets 75 in frame 73. A shoulder 76 on pins 71 and 72 cooperates with the springs 74 in a well known manner to bring the springs 74 in operating relation with the associated pin.

The pins 71 and 72 are engaged at their outer ends thereof and are respectively thrust forward by means of bell cranks 77 and 78 which are pivoted respectively at 79 and 80 upon ears 81 and 82 projected from the frame 73. These bell cranks 77 and 78 are respectively actuated through push rods 83 and 84 which have cam followers 85 and 86 at one end thereof rolling over the surface of cams 87 and 88. The springs 74 serve to maintain the cam followers 85 and 86 constantly in engagement with the surfaces of the cams 87 and 88. The push rods 83 and 84 are slidingly journaled respectively in blocks 83a and 84a which project from the frame 73.

The cams 87 and 88 are mounted upon the same shaft, which shaft rotates at an R. P. M. with respect to the R. P. M. of the impression cylinder in the ratio of 3:4. In the form of the device shown in Figures 11 and 12, the cams 87 and 88 are mounted on shaft 89 which is the shaft upon which the plate cylinder 52 is mounted. As such, the cams rotate at the same speed as the plate cylinder 52.

In the form of the device shown in Figures 14 and 15, the cams 87 and 88 are mounted on an auxiliary shaft 90 which is suitably journaled in frame 73. The shaft 90 is driven at a speed one-half as great as the speed of rotation of the plate cylinders 15 and 16. The operable connection between the plate cylinders and the auxiliary

shaft 90 is shown in Figure 15 as comprising a gear 91 mounted on the shaft 22 of plate cylinder 15 and a gear 93 mounted on the auxiliary shaft 90. The ratio of the pitch circles of gears 91 and 93 is 1:2 which means that gear 93 will rotate only once for every two rotations of gear 91.

It will be seen that in the form of the invention illustrated in Figures 1 and 12, the impression cylinder makes four revolutions for every three revolutions of the plate cylinder. In the form shown in Figures 14 and 15, the ratio of rotation of the impression cylinder to the plate cylinders during a complete cycle is 2:3 but the step-down gear ratio of gears 91 and 93 causes auxiliary shaft 90 to be rotated at one-half the speed of shaft 92. This means that the rate of rotation of the impression cylinder to the auxiliary shaft 90 is 2:1½, which when stated in whole numbers is the same as the ratio 4:3. By the simple expedient of varying the speed of rotation of an auxiliary shaft with respect to the speed of rotation of the plate cylinder, the same speed relationship between the impression cylinder and the cam shaft, upon which the cams 87 and 88 are mounted, is obtained.

The location of the tumbler actuating pins 71 and 72 is of great importance, for they must be positioned slightly before the point at which the grippers 42 are closed or opened. It can be seen by referring to Figures 7, 8, 9, and 10 that, for example, in the closing of the grippers 42, the tumbler 66 engages the pin 71 at a point before bottom dead center, where, theoretically, the grippers are to close on the sheet to be printed. Then, as the tumbler 66 continues to rotate about the center of the impression cylinder, the pin 71 being fixed, causes the tumbler 66 to rotate clockwise about the axis of the gripper shaft 62, causing the shaft 62 itself to be rotated. The grippers 42 mounted on shaft 62 move to the closing position which is shown in Figure 5.

As shown in Figure 8, the tumbler 66 has just moved to the closed position of grippers 42 and the gripper shaft 62 is just past bottom dead center at that point. Similarly, the pin 72 must be positioned so that the grippers 42 are opened when the gripper shaft 62 moves past approximately top dead center. It should, of course, be realized that if gripping or discharging of the sheet to be printed is to take place at other than bottom dead center or top dead center, such may be provided for by the correct positioning of the tumbler actuating pins.

Operation of the multi-color job or proof press

In the operation of the multi-color job or proof press shown in Figures 1 and 2, reference is called to Figures 6 and 7, wherein the tumbler 66 is positioned so that the grippers 42 are open and the pin 71 is thrust forward into the path of the tumbler 66 so as to close the grippers 42. The tumbler 66 is so positioned that the fingers 67 pass over the pin 71 causing the pin 71 to enter the pocket 68. The pin 71 engages the fingers 67 and causes the tumbler 66 to rotate clockwise about the axis of gripper shaft 62 as the tumbler 66 moves past the pin 71 in counter-clockwise direction. All the time the tumbler 66 is moving past the pin 71, pin 71 is moving deeper into the pocket 68. The pin 71 and the gripper shaft 62 are closest to each other when they are located upon a radius through the center of rotation of the impression cylinder 14.

As the tumbler 66 continues its counterclockwise rotation about the axis of the impression

cylinder 14, the pin causes the clockwise rotation of the tumbler 66 and the shaft 62 about the axis of shaft 62, thus closing the grippers 42. The pin 71 also serves to position the tumbler 5 so that the fingers 69 point in the direction necessary to grasp tumbler actuating pin 72 when the sheet which is printed is to be discharged. It will be noted that the attitude of the tumbler 66 as it leaves pin 71, as shown in Figure 8, 10 is the same as the attitude of the tumbler 66 when it is just grasping pin 72, as shown in Figure 9, for the purpose of discharging the printed sheet of paper.

Referring to the particular positions shown in 15 Figure 2, after the grippers 24 associated with impression surface 27 have grasped a sheet to be printed, there will be printed upon it the color which is carried by printing plate 33, and thereafter during the first revolution of the impression cylinder the sheet will also have printed on it the color carried by printing plate 32. Upon the second rotation of the impression cylinder 14, the same sheet will first engage the printing plate 34 and then engage the printing plate 31. After the impression surface upon 20 which the sheet to be printed passes plate 31, the tumbler 66, associated with the grippers 24 holding the sheet that has been printed in all four colors, will be actuated by pin 72 which is 25 thrust forward at the correct moment so that the sheet that is printed will be discharged onto the surface 13.

As shown in Figure 2, the grippers associated with the impression surface 27 have just been 30 opened and the sheet on the impression surface 27 is being discharged. As the impression cylinder continues to rotate, the grippers which are associated with the impression surface 27 will reach the position at bottom dead center shown in 35 Figure 2 as now occupied by the grippers associated with the impression surface 28. At this point the grippers will be actuated to closing position and will take on a fresh sheet to be printed.

It will be seen that a complete cycle of the impression cylinder includes two complete revolutions of the impression cylinder. The plate cylinders in the meantime are making three complete revolutions, and because of the difference in the number of surfaces between the impression cylinder and the plate cylinders, different colors are successively printed upon the same surface during the two revolutions of the impression cylinder. These colors are printed upon the sheet carried by each impression surface in the same sequence, as follows: yellow, red, blue and black. The reason why continuous operation of the impression and plate cylinders is possible with different colors being printed at all times in the same sequence is due to the aliquant ratio between the diameter of the impression cylinder to the diameter of the plate cylinder.

In the form of the job and proof press shown in Figure 3, the impression cylinder makes four revolutions for every three revolutions of the plate cylinder. Since the number of surfaces on the impression cylinder are three, and the number of surfaces on the plate cylinder are four, it is necessary that one impression surface on the impression cylinder pass the same point four times before each of the colors will be printed on a sheet carried by that impression surface. Once again the colors are printed upon each sheet in the same sequence.

11

As shown in Figure 3, the grippers associated with the impression surface 46 have just been opened and the sheet carried by the impression surface 46 is being discharged to the shelf 51. As the impression cylinder continues to rotate, the grippers associated with impression surface 46 are closed at bottom dead center of the impression cylinder and will pick up a fresh sheet to be printed. The next sheet to be discharged is carried on impression surface 44 and is shown being printed blue. Upon the next revolution the sheet on surface 44 will be printed black and then the sheet will be discharged. Impression surface 44 will then be ready for a fresh sheet to be printed.

Both of the forms of the job and proof press shown in Figures 2 and 3 are continuous machines which are continually discharging sheets which have been printed and picking up fresh sheets to be printed. For a single cycle of operation, in the form shown in Figure 3, the impression cylinder rotates four times, during which period three sheets have been discharged from the cylinder and three sheets have been taken on. The number of revolutions of the plate cylinder during a complete cycle is three. Thus, only a single cam for each of the pins 71 and 72 is necessary to actuate the pins 71 and 72, as for each revolution of the plate cylinder each pin is thrust forward only once and thus cooperates with one of the tumblers to discharge a sheet and to pick up a sheet.

In the form of the invention shown in Figure 2, three sheets will be discharged and picked up during two revolutions of the impression cylinder. For every two revolutions of the impression cylinder, the auxiliary shaft 90 rotates 1½ times and, therefore, two diametrically oppositely facing cams 87—87 and 88—88 to actuate each of the pins 71 and 72 are necessary so that each of the pins 71 and 72 will be actuated three times during a complete cycle of the auxiliary shaft 90 which comprises but 1½ revolutions. It will be obvious that the rotation ratios of the impression cylinder and the cams are such that each of the grippers associated with different impression surfaces are successively actuated, due to the inequality in angular travel between the impression cylinder and the cams.

With respect to the specific form of invention shown in Figures 2, 14, and 15, it will be observed that auxiliary shaft 90 rotates at one-half the speed of the impression cylinder shafts 22 and 23. Furthermore, auxiliary shaft 90 has two sets of opposite cams mounted thereon for actuating the pins 71 or 72. By mounting single cams for pins 71 and 72 on shafts 22 and 23, the same result can be obtained. Thus, a cam arrangement similar to that shown in Figures 11 and 12 may be mounted on either impression cylinder shafts 22 and 23.

The cams are so designed that the period during which one of the pins 71 or 72 is thrust forward is less than the angular displacement of one set of grippers with respect to the other set of grippers. In this way only one set of grippers will be actuated at a time, and thereby there will be no inadvertent actuation of the successive set of grippers.

This angular relationship is illustrated on the cam shown in Figure 13 which cam is one of those used in the form of the device shown in Figures 3, 11 and 12. The actuating pin is fully thrust forward for about 30 degrees of angular movement of the impression cylinder, which cor-

12

responds to 22½ degrees of angular movement of the cam. The operating region through which a tumbler passes, where the tumbler may be actuated by a pin, is in the neighborhood of 30 degrees of angular movement of the impression cylinder. Thus, the enlarged portion of the cam which actuates the push rods, bell cranks and pins, encompasses a maximum range of about 157½ degrees, which corresponds to an angular motion on the impression cylinder of about 210 degrees. Since the spacing between successive sets of grippers is 120 degrees, there is no possibility of pin 71 or 72, upon being thrust forward to actuate one set of grippers, inadvertently engaging the tumbler of the next successive set of grippers.

Some changes may be made in the construction and arrangement of the parts of my multi-color presses without departing from the real spirit and purpose of my invention, and it is my intention to cover by my claims any modified forms of structure or use of mechanical equivalents which may be reasonably included within their scope.

I claim as my invention:

1. A multi-color printing press comprising a single impression cylinder and at least one plate cylinder each having segments of equal peripheral length in the surfaces thereof adapted to register in tangential relation with each other, the circumferential length of the surfaces of the impression and plate cylinders each being an aliquot multiple, greater than unity, of the length of a segment, the circumferential length of a plate cylinder and the circumferential length of the impression cylinder being unequal by one segment length, means for rotating said impression and plate cylinders at the same peripheral speed, means including a plurality of printing plates positioned in said plate cylinder segments for printing a plurality of colors greater than the number of plate cylinders, means for retaining a sheet to be printed on each segment of the impression cylinder, a feeding station past which each impression cylinder segment passes as the impression cylinder rotates, means for feeding sheets consecutively to an arithmetical progression of said impression cylinder segments passing said feeding station, the number of consecutive impression cylinder segments skipped between one segment which receives a fresh sheet and the next segment receiving a fresh sheet being one less than the number of plate segments on a single plate cylinder, means for discharging a sheet from its impression segment after it has registered with each of the printing segments on the printing cylinders, means for feeding a fresh sheet to be printed on said vacated impression segment before said impression segment registers with any other plate segment, whereby fresh sheets are fed onto said impression cylinder continuously at equal intervals and whereby printed sheets are discharged from said impression cylinder continuously at equal intervals, and whereby each of the sheets carried by the impression cylinder is caused to register with each of the printing plates in the same predetermined sequence and beginning with the same color.

2. A multi-color printing press comprising a single impression cylinder and at least one plate cylinder each having segments of equal peripheral length in the surfaces thereof adapted to register in tangential relation with each other, the circumferential length of the surfaces of the impression and plate cylinders each being an

13

aliquot multiple, greater than unity, of the length of a segment, the circumferential length of a plate cylinder and the circumferential length of the impression cylinder being unequal, means for rotating said impression and plate cylinders at the same peripheral speed, the ratio of the total number of segments in the periphery of the impression cylinder to the total number of segments in the periphery of each plate cylinder being a fraction of lowest terms, means including a plurality of printing plates positioned in said plate cylinder segments for printing a plurality of colors greater than the number of plate cylinders, means for retaining a sheet to be printed on each segment of the impression cylinder, a feeding station past which each impression cylinder segment passes as the impression cylinder rotates, means for feeding sheets consecutively to an arithmetical progression of said impression cylinder segments passing said feeding station, the number of consecutive impression cylinder segments skipped between one segment which receives a fresh sheet and the next segment receiving a fresh sheet being one less than the number of plate segments on a single plate cylinder, means for discharging a sheet from its impression segment after it has registered with each of the printing segments on the printing cylinders, means for feeding a fresh sheet to be printed on said vacated impression segment before said impression segment registers with any other plate segment, whereby fresh sheets are fed onto said impression cylinder continuously at equal intervals and whereby printed sheets are discharged from said impression cylinder continuously at equal intervals, and whereby each of the sheets carried by the impression cylinder is caused to register with each of the printing plates in the same predetermined sequence and beginning with the same color.

3. A multi-color printing press comprising a single impression cylinder and at least one plate cylinder each having segments of equal peripheral length in the surfaces thereof adapted to register substantially in tangency with each other, the circumferential length of the surfaces of the impression and plate cylinders each being an aliquot multiple, greater than unity, of the length of a segment, the circumferential length of a plate cylinder and the circumferential length of the impression cylinder being unequal by one segment length, means for rotating said impression and plate cylinders at the same peripheral speed, means including a plurality of printing plates positioned in said plate cylinder segments for printing a plurality of colors greater than the number of plate cylinders, means for retaining a sheet to be printed on each segment of the impression cylinder, a feeding station past which each impression cylinder segment passes as the impression cylinder rotates, means for feeding sheets consecutively to an arithmetical progression of said impression cylinder segments passing said feeding station, the number of consecutive impression cylinder segments skipped between one segment which receives a fresh sheet and the next segment receiving a fresh sheet being one less than the number of plate segments on a single plate cylinder, means for discharging a sheet from its impression segment after it has registered with each of the printing segments on the printing cylinders, means for feeding a fresh sheet to be printed on said vacated impression segment before said impression segment registers with any other plate segment, said feeding

14

station being positioned adjacent said impression cylinder adjacent substantially the lowermost point of said impression cylinder, and a discharge station adjacent said impression cylinder spaced slightly below the uppermost point of said impression cylinder, both said feeding and discharge stations being positioned laterally of one side of a vertical plane through the axis of the impression cylinder, and the points of tangency of said plate cylinders with said impression cylinder being positioned laterally of the opposite side of said vertical plane.

4. A multi-color printing press comprising a single impression cylinder and at least one plate cylinder each having segments of equal peripheral length in the surfaces thereof adapted to register substantially in tangency with each other, the circumferential length of the surfaces of the impression and plate cylinders each being an aliquot multiple, greater than unity, of the length of a segment, the circumferential length of a plate cylinder and the circumferential length of the impression cylinder being unequal by one segment length, means for rotating said impression and plate cylinders at the same peripheral speed, means including a plurality of printing plates positioned in said plate cylinder segments for printing a plurality of colors greater than the number of plate cylinders, means for retaining a sheet to be printed on each segment of the impression cylinder, a feeding station past which each impression cylinder segment passes as the impression cylinder rotates, means for feeding sheets consecutively to an arithmetical progression of said impression cylinder segments passing said feeding station, the number of consecutive impression cylinder segments skipped between one segment which receives a fresh sheet and the next segment receiving a fresh sheet being one less than the number of plate segments on a single plate cylinder, means for discharging a sheet from its impression segment after it has registered with each of the printing segments on the printing cylinders, means for feeding a fresh sheet to be printed on said vacated impression segment before said impression segment registers with any other plate segment, said feeding station being positioned adjacent said impression cylinder adjacent substantially the lowermost point of said impression cylinder, and a discharge station adjacent said impression cylinder spaced slightly below the uppermost point of said impression cylinder, both said feeding and discharge stations being positioned laterally of one side of a vertical plane through the axis of the impression cylinder, the points of tangency of said plate cylinders with said impression cylinder being positioned laterally of the opposite side of said vertical plane, and the plate cylinder carrying the last printing segment to register with a sheet before it is discharged from said impression cylinder being positioned tangent to said impression cylinder at a point spaced from said discharge station a distance, along the periphery of said discharge cylinder, at least the length of one segment, whereby the sheet to be discharged is completely free of engagement of any printing plate before the first portion of the sheet begins to be discharged from the impression cylinder.

5. A multi-color printing press comprising a single impression cylinder and a single plate cylinder having equal segments in the surfaces thereof adapted to register with each other, the peripheral length of the surfaces of the impres-

15

sion and plate cylinders each being an aliquot multiple, greater than unity, of the length of a segment, the peripheral length of said impression cylinder comprising three said segments and that of the plate cylinder comprising four said segments, means for rotating said impression and plate cylinders at the same peripheral speed, a printing plate in each said plate cylinder segments for printing a different color ink, means for retaining a sheet to be printed on each segment of the impression cylinder, a feeding station past which each impression cylinder segment passes as the impression cylinder rotates, means for feeding sheets consecutively to an arithmetical progression of said impression cylinder segments passing said feeding station, the number of consecutive impression cylinder segments skipped between one segment which receives a fresh sheet and the next segment receiving a fresh sheet being three, means for discharging a sheet from its impression segment after it has registered with each of the segments on the plate cylinder, means for feeding a fresh sheet to be printed on said vacated impression segment before said impression segment registers with any other plate segment, whereby fresh sheets are fed onto said impression cylinder continuously at equal intervals and whereby printed sheets are discharged from said impression cylinder continuously at equal intervals, and whereby each of the sheets carried by the impression cylinder is caused to register with each of the printing plates in the same predetermined sequence and beginning with the same color.

6. A multi-color printing press comprising a single impression cylinder and a pair of plate cylinders, said plate cylinders having equal segments in the surfaces thereof adapted to register with equal segments in the surface of the impression cylinder, the peripheral length of the surfaces of the impression and plate cylinders each being an aliquot multiple, greater than unity, of the length of a segment, the peripheral length of said impression cylinder including three said segments and that of each plate cylinder

16

including two said segments, means for rotating said impression and plate cylinders at the same peripheral speed, a plurality of printing plates on said plate cylinders for printing a plurality of colors greater than the number of plate cylinders, means for retaining a sheet to be printed on each segment of the impression cylinder, a feeding station past which each impression cylinder segment passes as the impression cylinder rotates, means for feeding sheets consecutively to an arithmetical progression of said impression cylinder segments passing said feeding station, the number of impression cylinder segments skipped between one segment which receives a fresh sheet and the next segment receiving a fresh sheet being one, means for discharging a sheet from its impression segment after it has registered with each of the segments on the plate cylinders, means for feeding a fresh sheet to be printed on said vacated impression segment before said impression segment registers with any other plate segment, whereby fresh sheets are fed onto said impression cylinder continuously at equal intervals and whereby printed sheets are discharged from said impression cylinder continuously at equal intervals, and whereby each of the sheets carried by the impression cylinder is caused to register with each of the printing plates in the same predetermined sequence and beginning with the same color.
